UNITED STATES PATENT OFFICE

JOSEPH BLONDIN, OF LOS ANGELES, CALIFORNIA

CANARD TYPE AIRPLANE

Application filed July 5, 1929. Serial No. 376,230.

This invention relates to aircraft and particularly to airplanes of the "canard" type comprising main lifting surfaces or wings and a "loaded" or weight carrying front elevator supported by a frame work extending forward of the main wings.

Aviation history chronicles many canard types of airplanes which flew more or less successfully and all of which were characterized by superior qualities of fore-and-aft stability compared with other types of airplanes. But they were all inferior in response to "rudder action," i. e., to being steered sidewise.

An object, therefore, of this invention is to successfully modernize the canard-type airplane retaining and improving its qualities of fore-and-aft stability, and endowing it with efficient rudder-action which it has heretofore lacked.

Pioneer canard-type airplanes were also defective in that element of structure which was depended upon to support the front elevator. In the case of biplanes such element was an "outrigger frame" attached to and projecting forward from the wings. Such outrigger-frames were inherently weak because of length and lightness, and lack of resistive factor to lateral and torsional stresses. In the case of monoplanes such elevator carrying element was a central, quadrangular or "box-truss" frame forming an integral extension of the nacelle or car and was supported clear of the ground by the running gear which consisted, generally, of two side wheels at the rear portion of the frame, and one central wheel set far forward on the frame. This frame, while capable of being made more rigid and stronger for a given weight than the biplanes outrigger was, however, handicapped by being made to also carry the said forward wheel unit of the running gear thereby being forced to absorb the violent stresses placed on the wheel-unit at take-off and landing, and ground running, and these stresses were imposed upon said box-frame close to its extreme forward end, or at its point of free "overhang," or unsupported leverage.

A further object, therefore, is to provide a front-elevator supporting structure of maximum rigidity and resistance to all ver-

tical, lateral and torsional stresses that might be imposed by the elevator, and to eliminate the conventional forward wheel-unit as used in the past, thus relieving the forward extending, free overhang portion of the frame from all landing stresses and limiting it to its single, proper function of supporting the front elevator. To this end I have invented and provided an inverted, triangular-trussed keel-frame which not only supports the front elevator but underlies and directly and incidentally supports all other constructional and operative elements of the airplane proper. By the present invention for over two-thirds of its length the keel frame supports the nacelle or car and is in turn reinforced and strengthened by the rigidity and inertia of the car and its loads.

A further object is to provide a skid frame of inverted triangular form whose rear and lowermost end is adapted to engage the ground when landing and further, whose apex-beam or keel will act as a runner at its rearmost end and at any other portion in its length, in emergency, such as might occur if the wheels dropped into a ditch or the furrows of a plowed field. Note that in either case this invention designs the skid-feature to function directly under the car whose rigidity and inertia will absorb all landing stresses.

More directly, the landing gear proper consists, here, of the rearmost and lowermost portion of the triangular keel-frame in combination with a plurality of side wheels widely spaced laterally from the sides of the car of the airplane; the keel-frame having a yieldable shoe. All previous canards were characterized by the employment of a single elevator surface carried forward of the machine's center of gravity, whose carrying capacity, as a wing, and directional capacity, as an elevator was depended upon to govern the inherent stability, trim and climbing and diving maneuvers of the airplane.

An additional object of this invention is to supplement the above referred to conventional front elevator and materially improve the control of such canard type planes by adding a rear elevator carried rearward of the ma-

chine's center of gravity and hinged to the rear wing-bar of the main lifting planes; this being entirely original conception in canard type airplanes, and greatly enhancing 5 control of the machine's fore and aft balance and direction, and made effective distinctive- 10 ly by my provision wherein the center of gravity of the machine, in flight, is main- tained forward of the main lifting wings and not below as heretofore the case.

Another object is to provide a superior 15 means for aircraft steering, particularly canards, around their vertical axis. All previous canard planes were deficient in sidewise 20 steering action, their lack of proper keel or vertical fin to complement their rudder sur- face being adjudged the reason for the defect. Now, in the first place, none of the pioneer canards, actually built carried their center 25 of gravity sufficiently forward.

The location of this fundamental govern- 30 ing point was, in most cases, positioned di- rectly under the wings leaving insufficient leverage for the rudder to act upon. The 35 operation of a single vertical rudder, so handi- capped, resulted more in an outward skid than a true turn—a skid which immediately entailed loss of lateral stability, followed by 40 stalling or diving effects which quickly de- famed the canard principle of design.

Remedy of this defect usually took the 45 form of extra vertical surfaces or fins placed forward of the wings upon the framework which supported the front elevator. These 50 furnished the needed fulcrum for the rudder to act against but they, at the same time, furnished an added "fin surface" with long le- 55 verage from the machine's center of gravity for any and every side gust or current of wind 60 to act upon. Thus the rudder action was again minimized—or even nullified—the ma- chine in such case being turned "down wind" with a consequent greater loss of lateral sta- 65 bility than in the former case. Also, a single 70 rudder located following the exact longitudinal axis of any vessel acts detrimentally in the sense that the "drag" component serves 75 to retard the speed of the vessel and, con- sequently, to reduce fluid reaction against the 80 rudder surface; action whose efficiency in- creases as the square of the speed of the ves- 85 sel. Obviously, such rudders contribute only the side component or thrust of their over- 90 all possible steering efficiency. I seek to ob- 95 tain a maximum effective steering action through, first—placing the center of gravity 100 of the machine at a point situated at least 25% of the wing chord in front of the leading 105 edge of the main wings thereby increasing the 110 rudder's leverage to said center: second—by 115 provision of twin rudders operative outward 120 only as to the ship's longitudinal axis: third—provision of means to operate each 125 twin rudder independent of the other so that 130 but one is effective on turns while the other

lies in the "bed of the wind" or at zero angle to the flight line: fourth—the provision of 70 rudders placed off the longitudinal axis of the machine at a considerable distance so that each rudder acts jointly in response to side thrust and to backward drag as well, on lever 75 arms whose magnitudes are measured for- ward to the center of gravity of the machine and laterally to the long axis respectively: fifth—the provision of a preponderance of 80 constructional vertical surfaces rearwardly of the center of gravity of the machine so that all side-gusts or currents of wind, in flight, will tend to turn the machine "into the wind"; the correct position for maintaining the sta- 85 bility of the machine.

A still further object is to provide means to utilize the "drag" effect of the rudder con- 90 junctively to reduce the momentum of the machine when landing and thus shorten the "run" after first touching ground. To this end means are provided for separate turn 95 and for concurrent brake action through the instrumentality of rudders.

Still another object is to provide "wind- 100 frame" struts so disposed as to rise vertical- 105 ly from lateral beams from the chassis to superjacent main cantilever wings and to perform the important function of supporting the wing at a material distance outward 110 from the nacelle or car, thus reinforcing the cantilever wing by reducing the length of its free overhang. In full cantilever wing ma- chines the overhang extends from the fuse- 115 lage or car side to the extreme tip of the wing. 120

In the present disclosure the wing's over- 125 hang extends only from the window-frame struts outward to the tips of the wings; a reduction in length furnishing greater stiff- 130 ness to the wings and reinforcement against compression and bending stresses in the internal structural members of the wings.

My invention has for particular objects 135 therefore, first—the improvement of the air plane type of aircraft and espe- cially all canard type airplanes by incorporating the 140 keel frame as an element of the landing gear and to unite, strengthen and support all other elements of the machine; second—the 145 provision of a canard type which places the 150 center of gravity entirely forward of its main lifting planes, and third—the provi- 155 sion of operative means improving the sta- 160 bility and the control of the balance and of the flight direction of the machine.

Other objects, advantages and features of 165 construction, combination and details of 170 means and mode of operations will be made 175 manifest in the ensuing description of the 180 herewith illustrative embodiment; it being 185 understood that modifications, variations 190 and adaptations may be resorted to within 195 the spirit, scope and principle of the invention 200 as it is more directly claimed hereinafter.

Figure 1 is a plan of the airplane.

Figure 2 is a side elevation thereof.

Figure 3 is a front elevation, and

5 Figure 4 is a diagram showing the relative position of the rudders to the ship's center of gravity.

In the illustrated ship a front elevator A is disposed well ahead of the main lifting surface or wing B; both being solidly fixed 10 on a skeleton chassis into which is built the nacelle or car N. The skeleton extends well forward from the car and is characterized by an inverted triangular or V-section keel-frame K which presents a bottom, longitudinal apex-beam or keel K' the full length 15 of the ship; having at its rear end a hinged heel piece P supported yieldably by a bow spring P' based on the rear end of the body frame.

20 The wings include spaced upper cross-beams I—I on the top of the cabin of the car N and each wing is secured to the top stringer of respective, outboard, vertical "window-frame" struts J whose posts stand on laterally projecting, transverse beam I'— which thus serve to greatly strengthen the overhead wing structure.

The intraspaces of the window-frame struts J are provided with fin-surfaces L in 30 front of rudders E hinged to the vertical, rear posts of the struts; the latter having diagonal braces J' which reinforce and stiffen the fin frames J and form trusses whose king post is the nacelle or car.

35 Above the forward or nose part of the keel-frame K is a supplementary V-frame K'' which materially stiffens and reinforces the frame K as the support for the front elevator and incidentally forms a harmonizing superpart for the keel-frame.

A notable feature of this airplane is the arrangement of the main wing B at the extreme rear of the chassis and the placing of the car and the front elevator to produce the 45 center of gravity of the machine well forward of the main wing; preferably at a minimum distance equal to 25% of the wing-chord, and being indicated by the point G; whereby to achieve inherent stability.

50 The ship is provided with ground wheels W widely spaced from the sides of the keel-frame and with the keel-beam K' or heel P providing for three-point landing contact and rest supports. The wheels are forward 55 of the rear end of the frame K and should they drop into surface depressions the keel K' comes into effect as a sliding skid.

The rudders E are independent and are 60 operated by independent foot treadles F' so that only that rudder is actuated which is on the side of the ship relative to an intended turn; the right foot controlling the right rudder for a right turn and the left foot for a left turn in the usual manner. Another 65 advantage of this system is that, at will, the

pilot may throw out both rudders at one time with the result that a decided braking effect is accomplished; this being effected by pressure of both feet on the rudder controls at the same moment.

70 The improved rudder system and organization is graphically set forth in Fig. 4 which shows the offset relation of the rudders E to the longitudinal axis X. The line a indicates the drag having a turning moment in arc a' about the center of gravity on a radius or lever equal to the distance of the rudder post of strut J from the ship's axis; force b acts on arc b' with leverage to the point G.

75 Vertical flight control is facilitated by a hinged trailing surface or flap A' attached to the front elevator A, and a rear elevator surface or flap B' hinged to the trailing edge of the plane B and connected to the front flap A' by a control means of conventional form operative to concurrently tilt the flaps in opposite directions; i. e. the forward one up and the latter down to pull the nose down and vice versa to raise the nose, so that each 80 flap acts with a cooperative movement about the center of gravity G of the machine.

85 It will be noted that there is no material vertical surface at the nose of the fore-rig frame carrying the front elevator means thus 90 eliminating objectionable counteraction by side pressure of the air when turning and avoiding side drift of the head due to lateral air currents.

The driving propeller is here shown as at 100 the rear of the car N.

In the take-off position the machine rests on its three-point base P—W—W, with the nose of the ship directed well up from the ground line Y.

105 Lateral stabilizing ailerons O are hinged to the main wing B outward of the medially disposed rear elevator element B'.

What is claimed is:

1. In a canard-type airplane, a triangular, 110 trussed skeleton keel-frame whose members are permanently attached to form a unitary longitudinal girder with its apex-beam lowest and whose upward base forms a platform supporting at its forward end a front elevator, at its median portion supporting a superimposed car and its rear end having a superimposed main wing structure the inverted beam forming a landing tail.

115 2. In a canard airplane, an integral triangular, trussed keel-frame which underlies and supports the machine's front elevator surfaces and a superimposed car and propelling means and main wing, and lateral fin frames carried by the keel-frame and having trailing rudders; said frames forming outboard supports for cantilever parts of the wing.

120 3. In a canard airplane, a triangular-section skeleton keel-frame with its apex-beam 125

- downward and constituting a ship-length keel and its upward base forming a platform for superimposed planes and superimposed car structure; the rear end of the said beam 5 forming one point of landing and resting support for the airplane.
4. In a canard airplane, a triangular-section, trussed keel-frame with its apex-beam downward and forming a ship-length keel, 10 and a supplementary, triangular nose frame with its base imposed on the upward base of the keel frame.
5. In a canard airplane, a triangular, trussed keel-frame with its apex-beam downward and whose extention represents the over-all length of the airplane, the rear end of the said beam forming a landing support, and wide spaced ground wheels at the sides 15 of the frame and forming with the rear end of the beam a three-point landing and standing support.
6. In a canard airplane, a fixed forward, elevating plane, a rearward main plane, and 20 cooperative elevator flaps on said planes and respectively fore and aft of the ship's center of gravity.
7. A canard airplane having, in combination, a front elevator having a trailing edge flap, and a main wing having a trailing edge 25 flap coupled to the front flap for coaction with respective movements in opposite directions.
8. A canard-type airplane in which the center of gravity is forward of the leading 30 edge of the main plane at a minimum distance equal to 25% of the chord of the wing, and having elevator means including control flaps fore and aft of the center of gravity.
9. In a canard airplane, vertical rudders 35 having laterally outboard supports and spaced beyond the respective sides of the long axis of the machine and operative separately to make a respective turn of the machine; the idle rudder being free to hang at zero 40 angle to the line of flight and adapted for concurrent operation in opposite outward direction to serve as brakes, the braking rudders being disposed rearward of the center 45 of gravity of the machine.
10. In a canard airplane, a pair of vertical rudders each offset from the longitudinal 50 axis of the machine and rear of its center of gravity and separately operative; whereby the active rudder induces a backward drag 55 acting on a leverage measured sidewise from the rudder post to the said axis and simultaneously induces a side thrust acting on a leverage measured forward from the rudder 60 post to the center of gravity of the machine so that each rudder has a double turning couple in steering action and means for concurrently turning the rudders in opposite directions outwardly as brakes effective rearward- 65 ly of the center of gravity of the machine.
11. In a canard airplane, a chassis including spaced, horizontal beams extending laterally of the ship's axis, outwardly spaced window-frame struts standing on said beams and whose intra-frame spaces have fin surfaces; the bottom stringers of the frames being attached to said beams and whose top stringers are secured for their length to the arch of the airplane's main wing; said frames reducing the length of the free overhang of the wing structure.
12. In a canard airplane, a chassis including spaced, horizontal beams extending laterally of the ship's axis, outwardly spaced window-frame struts standing on said beams; the bottom stringers of the frames being attached to said beams and whose top stringers are secured for their length to the arch of the airplane's main wing; said frames reducing the length of the free overhang of the wing structure.
13. In a canard airplane, a main wing and rudder supports fixed thereto laterally of the ship's axis, one on each side and rear of the ship's center of gravity, and independently operative rudders on said supports, and means to set the rudders concurrently as brakes.
